Patented May 12, 1903.

UNITED STATES PATENT OFFICE.

HERBERT F. BLOGG, OF NEW HAVEN, CONNECTICUT.

DESIGN FOR A BADGE OR SIMILAR ARTICLE.

SPECIFICATION forming part of Design No. 36,314, dated May 12, 1903.

Application filed March 20, 1903. Serial No. 148,799. Term of patent 3½ years.

To all whom it may concern:

Be it known that I, HERBERT F. BLOGG, a citizen of the United States, residing at New Haven, in the county of New Haven and State of Connecticut, have invented and produced a new, original, and ornamental Design for Badges or Similar Articles, of which the following is a specification, reference being had therein to the accompanying drawing, forming part thereof, which illustrates a front elevation of a badge showing my design.

As shown in the drawing, the badge is constructed with a body member 1, a pendant 3, suspended below the body member, and a plurality of smaller pendants 4, set with stones 5.

The leading or material feature of my design consists of a panel 2, surmounted by an eagle with spread wings having the national shield upon its breast, a plurality of imple-

ments of war radiating from said panel, on either side thereof, and comprising flags, battle-axes, horn of plenty, cannon, swords, drum, baton, and scales of justice.

The configuration of the pendant 3 is that of a scroll, with an anchor intermediate between said pendant and said body member.

Having described my invention, what I claim as new, and desire to secure by Letters Patent, is—

The ornamental design for a badge, or similar article, as herein shown and described.

In testimony whereof I affix my signature in presence of two witnesses.

HERBERT F. BLOGG.
